(74) Attorney, Agent, or Firm—Michael P. Leary; Adan Ayala

(57) **CLAIM**

The ornamental design for an impact driver, as shown and described.

DESCRIPTION

FIG. 1 is a right/front perspective view of an impact driver showing my new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.
